UNITED STATES PATENT OFFICE.

ALFONSO CORTELLA, OF PHILADELPHIA, PENNSYLVANIA.

TALKING-MACHINE.

1,274,690.

Specification of Letters Patent.

Patented Aug. 6, 1918.

Original application filed August 21, 1913, Serial No. 785,853. Divided and this application filed January 22, 1917. Serial No. 143,614.

To all whom it may concern:

Be it known that I, ALFONSO CORTELLA, a subject of the King of Italy, and a resident of Philadelphia, county of Philadelphia, and 5 State of Pennsylvania, have invented an Improvement in Talking-Machines, of which the following description, in connection with the accompanying drawings, is a specification, like characters on the drawings representing like parts.

This invention relates to sound reproducing machines and aims to provide a novel machine of this type adapted for playing a plurality of records successively and in repeated cycles, whereby the records may be played without interruption, thus making possible a reproduction of any desired length.

My invention comprehends a talking machine having a plurality of preferably continuously operative record carrying members, and automatic means for throwing these record carrying members into operation successively and, as stated, in repeated cycles.

This application is a division of my application Serial No. 785,853.

Referring to the drawings of the illustrative embodiment of my invention selected 30 for description and illustration herein—

Figure 1 is a front elevation;

Fig. 2, a plan;

Fig. 3, a front elevation of the shifting mechanism for throwing the records successively into and out of operation;

Fig. 4, a plan thereof;

Fig. 5, a vertical section on the line 5—5, Fig. 3, from the right showing a detail of the means for locking a record into operative 40 relation with its carrying member, herein a turntable;

Fig. 6, a vertical sectional view on the line 6—6, Fig. 3, of further details of the shifting mechanism;

Fig. 7, an enlarged detail of the means for locking the record to the continuously operative carrying member, and

Fig. 8, a side elevation of one of the turntables, with the sound arm mounting in vertical section, and showing also the connection between the sound arm and shifting

mechanism to actuate the latter for successively locking and unlocking the records to their respective turntables.

Referring now to Figs. 1-3, my novel 55 talking machine is shown as comprising a suitable table or stand 1, conveniently supported, as by hollow legs 2 adapted to receive therein sliding rods 3, which may be adjustably locked thereto by means of set 60 screws 4 so that the table may be adjusted to any height to suit varying conditions, as desired.

Mounted on the table 1, Figs. 1, 2, at suitable points, are a plurality, herein two, of 65 turntable supports or frames 5, 5, which may be secured to the table in any convenient manner as by bolts 6. The top member 7 of each frame, and also the bottom member 8 are each drilled vertically to provide 70 bearings for the hollow turntable shaft 9 which rotates therein. Each shaft 9 may be, if desired, provided with roller bearings 10, shown here of conventional form.

Adjacent the shaft 9, 9, and herein in the 75 rear of the same, Figs. 1, 2, and 3, is located a driving shaft 11 and provided with a pulley 12, by means of which power may be transmitted to said shaft from any convenient source, as a motor 12^a, for instance, beneath the table 1. The shaft 11, see Fig. 2, is provided with a plurality of gears 13, 13, each in mesh with a gear 14 on one of the shafts 9, whereby rotation is imparted to the turntables 15, 15, mounted on the upper ends 85 of said shafts.

The turntables 15, 15, are both adapted to be, and preferably are, always in rotation with the shaft 11, as will be more fully described later, and I term them for convenience, simultaneously operative record-carrying members. The records 16, 16, are adapted to be held secured to their respective successively operative record supports or carrying members 17, 17, and successively locked 90 to the turntables at the proper times by a novel means for that purpose. The record carrying member 17 is here shown, see Fig. 7, as a pintle mounted within the shaft 9, normally freely rotatable therein and extending above and below the same, and provided on its upper end with a nut 18 for

locking the record between the same and a ring or shoulder 19 on the pintle 17.

The upper end of each shaft 9 is provided, Fig. 7, with a shoulder 9^a, for receiving the turntable thereon and said upper end is counter-bored and provided with a crown gear 20 while each ring 19 is provided with a single depending tooth 21, Fig. 7, adapted to engage the teeth of the crown gear 20 when its record is in operation.

For both unlocking the successively operative record carrying member 17 from the turntable and its shaft, and for supporting the same while in unlocked or inoperative position, I have provided the following novel construction. Just below the lower end of each shaft 9, Figs. 1, 3, is a pintle and record supporting member 22, which normally supports the lower end of the pintle, when in inoperative position with its tooth 21 raised above and out of engagement with the crown teeth 20, as at the right-hand end of Fig. 1. This member 22, when the pintle is in operative position, however, as at the left, Fig. 1, is dropped somewhat below the end of the pintle, permitting the latter to drop down in the shaft 9 and the tooth 21 to engage the crown teeth 20, Fig. 7, and lock the record 16 to its turntable 15 and shaft 9, and to cause it to rotate with said turntable and shaft.

As previously stated the two turntables are so connected with the operating shaft 11 that they are both always in operation but I have provided novel record-shifting means, including the pintle supports 22, 22, just referred to, for alternately throwing the pintles and the records secured thereto into operation and this record shifting means I will now describe.

It is obvious that it is particularly desirable that means be provided that will shift the records so quickly that no noticeable interruption in the reproduction thereof will occur. At any suitable point, therefore, between the two turntables, and preferably substantially midway thereof, is provided a support 23 on the table 1, for the record shifting lever or walking beam 24, which is pivoted thereto by a pin 25.

This support 23 is, in this case, Fig. 6, an angle iron having a base 23^a and rear upturned member 23^b provided with lever guides 23^c. The lever 24 is preferably a long thin member provided at suitable points thereon, as at each end, with pintle supports 22, 22, previously referred to, and secured thereto as desired, as by screws 26, Fig. 5.

It will be noted from the construction so far described that necessarily when one end of the lever 24 with its corresponding pintle support is depressed, the opposite end, with its corresponding pintle support and pintle, is raised, so that necessarily one pintle with its record is locked to its shaft 9 while the

opposite pintle and its record is unlocked from its shaft 9.

The controlling means for the shifting mechanism, herein comprises, Figs. 3, 4, 6, bellcrank locking and unlocking levers 27, 70 pivoted to suitable supports 23^b on the table 1, the short arm of each lever bent or otherwise adapted to engage a catch 28, on the rear face of the lever 24.

The long arm of the lever 27 is extended 75 to form a cam surface 29 adapted to be engaged by a lever tripping member 30, see Fig. 2, in dotted lines, depending from and adapted to be actuated by the sound arm, and to be more fully described presently. 80 These levers 27 are each normally retained in locking position by means of a leaf spring 31, one end of which is secured thereto, while the opposite end is seated upon the table 1.

For depressing and locking one end of the 85 lever 24 instantly upon the unlocking and raising of the opposite end of said lever, and thus instantly shifting the records, I have invented the following novel mechanism, forming also part of the shifting lever controlling means.

On the front face of the lever 24, see Figs. 3, 4, 5, near each end, is secured a bracket 32, and to the bracket are pivoted rearwardly extending lever positioning members 95 33, 33^a. These lever positioning members, see Fig. 4, are somewhat narrower at their rear ends than at their forward ends, and each has pivoted thereto on its upper face and substantially parallel therewith, a yielding 100 mounted catch 34 provided with a slot 35 on one edge thereof to engage a pin 36 on the lever positioning member 33 beneath. Each catch is normally held in that position by a leaf spring 37 thereon bearing against 105 a pin 38 also extended upwardly from the upper face of the member 33, and acting as a stop on that side of the member 34 for the same.

Positioned between said members 33, 33^a, 110 and on the support 23^b are pivoted two upright reversing levers 39, 39, each suitably positioned to be engaged by one of the trip members 30, 30, already referred to, immediately after the member 30, in its travel laterally depresses the cam end of one of the locking levers 27, 27. These reversing levers 39, 39, are each pivotally connected by a connecting rod 40 with the lever positioning member 33 or 33^a at the opposite ends of 120 the lever 24, and each is normally retained in proper position by a spring 41, secured thereto and to the member 23^b or any convenient support.

For positively acting upon the lever positioning members 33, 33^a, at the proper time to cause them to depress the respective ends of the shifting lever 24, I have provided lever shifting disks 42 mounted upon and rotated by the shaft 11. These disks may be 130

adjusted upon the shaft 11 both longitudinally and circumferentially by means of screws 43. Each disk has a roll 44 mounted thereon which, on rotation of the disk 42, 5 will engage the upper face of the lever positioning member 33, or 33^a, when it is in proper position for said engagement, to depress one end of the lever 24 and its pintle supporting member 22 and thus also act to 10 raise the opposite end of the lever 24, its pintle support and pintle.

The trip members 30, 30, are shown, Fig. 8, as depending rods with laterally bent ends carrying rolls 45, 45, the rods threaded near 15 their upper ends and provided with nuts 46, 46, disposed, respectively, Figs. 2, 8, above and below the ends of clamp members 47, 47. These members are secured about the necks 48, 48, of the sound arms 49, 49, movably 20 mounted in the two branches of the sound carrying tube 50.

Each trip member is so adjusted as to position on the neck 48 of the sound arm that it will trip the lever 39 when its roll 25 45 is pushed against the same by the traveling sound arm 49. This happens when the needle 51 of the sound box 52 having completed the reproduction of the record, is fed laterally or across the record sufficiently far 30 to cause the roll 45 to engage the member 30, and this result is accomplished very satisfactorily if the sound arm is quickly deflected laterally by a distorted or sharply pitched portion 53 of the groove at the end 35 of the groove 54.

For supporting each sound arm 49 above and out of contact with its record or turntable when not in use or when the record is to be changed, I have provided, Figs. 2, 8, 40 on the upper end of the sound conveying tube 50 and adjacent each neck 47, a cam track 55 on which the clamp 47 slides as the sound arm is swung laterally to the right and away from the turntable, and this cam 45 55 gradually raises the sound arm 49 and box 52 to a convenient inoperative position.

The sound tube 50, Fig. 1, is shown forked near its upper end, one arm leading to each sound arm 49. The lower end of the sound 50 tube is carried down through the table 1, extended laterally and provided with a horn, not shown, or if desired, with any suitable sound magnifying device 56, and by means of a wire 57 or other convenient arrangement, the sound may be conveyed to any 55 part of an auditorium.

The sound tube 50 is herein shown as contained within a case 58 but this may be dispensed with if desired.

60 The operation of my improved talking machine is as follows: The records are first made on the foregoing described or other suitable machine, by substituting a record making needle or recorder for the reproducer. The record 16 of the first portion of

the piece to be reproduced is then placed upon either turntable, for instance, the left-hand one, Fig. 1. The record is secured to its pintle 17, see Fig. 7, by removing the nut 18 therefrom thrusting the top of the pintle 17 therethrough and then screwing the nut down securely thereon, locking the record between the nut and the flange 19.

The record 16 containing the balance or next section of the piece is placed in position 75 in the same manner on the right-hand turntable. The left-hand end of the lever 24 is then depressed until the tooth 28 on the rear face thereof is engaged by the lever 27, thus permitting the pintle 17 to drop within the hollow shaft 9 until the tooth 21 on the flange 19 engages the crown teeth 20 on the upper end of the shaft 9.

The lever positioning members 33, 33^a, will be in the position shown in Fig. 4, the 80 right-hand end of lever 24, Fig. 3, supporting the right-hand pintle 17 with its record in raised or inoperative position, Fig. 1. Both needles are placed at the beginning of the respective records, one record, the left-hand one, being in operative position and the other in inoperative position. The motor 12^a or other source of power is now 85 started and the turntables 15, 15, thus put into operation by means of the pulley 12 90 and common shaft 11.

As already stated, the record groove is preferably provided at its end with a short 95 relatively sharp lateral extension 53. The lever tripping member 30 is so adjusted on the clamp 47 as to height, and said clamp so adjusted circumferentially about the neck 48, that the roll 45 on said member 30 will engage the cam face 29 of the lever 27 to throw the same and unlock it from the catch 28 on the lever 24 approximately an instant before the needle 51 reaches the lateral extension 53 at the end of the record. The roll 45 thereafter still moving laterally, will 100 then engage the lever 39 as soon as the record is finished and the needle enters the lateral extension 53, which causes a quick movement of the roll 45 against said lever.

When the roll 45 engages the lever 39 it 105 then, by reason of the link 40 connecting the lever 39 with member 33^a, causes said member 33^a to be thrown to the left, Fig. 4, into the path of the roll 44 on the Fig. 4 right-hand disk 42. If when said member 33^a is 110 thus thrown laterally, the yielding catch 34 thereon should happen to engage edgewise the roll 44, said member 34 will yield against the spring 37 until the roll has passed beyond its plane, the narrow outer end of the member 33 permitting this 115 when the catch 34 will be immediately thrown again into the path of the roll 44 by said spring 37. On its next revolution, or its first revolution if said edgewise contact did not take place, the roll 44 will engage 120 125 130

the upper face of the member 34 and depress the same with that end of the lever 24 bringing the catch 28 thereon beneath the hooked end of the spring pressed lever 27, 5 the spring 31 throwing the lever 27 forward and locking the lever 24 in that position.

When that end of lever 24 is depressed the pintle supporting member 22 thereon is also depressed permitting the pintle 17 10 and record 16 locked thereto, hitherto in inoperative position to fall into operative position, the tooth 21 on the pintle 17 engaging the crown teeth 20, and imparting the motion of the Fig. 1, rotating right-hand 15 turntable to the record 16.

By the same motion of the lever 24, the left-hand, hitherto operative, record is withdrawn into inoperative position by being raised by the rising left-hand end of lever 20 24 and member 22 until the tooth 21 on said pintle is disengaged from the teeth 20, on the shaft 9. While this record is in inoperative position, it may be replaced by a record bearing another piece or another section 25 of the same piece for reproduction. For this purpose, the sound arm may be swung to the right until it rides upon the cam 55 where it will be supported.

When the new record has been placed on 30 the left-hand pintle 17 and the needle again placed in position at the beginning of the groove, the record is again ready to be automatically placed in operation by a repetition, in the reverse direction, of the foregoing 35 described operation of the trip member 30, actuated by the levers 27, 39, and shifting of lever 24, raising the right pintle and record and lowering again the left-hand pintle and record.

40 Obviously this operation of the talking machine may be continued without any noticeable interruption of the reproduction of the record as long as desired, and completely overcoming the objectionable delays and interruptions hitherto occasioned by changing the records.

Obviously, by using recording styli instead of reproducing styli, the foregoing embodiment of my invention may be used 50 for recording sounds as well as reproducing them, and many features of the invention, such as the successive operation in repeated cycles of the record carrying members would be as advantageous when the machine was so used.

While the above embodiment of my invention provides a most satisfactory form of construction, it may be possible to vary the same in many respects within the spirit 60 of the invention and the scope of the appended claims.

Claims:

1. A sound recording and reproducing machine comprising a plurality of record carrying members, an independently opera-

tive record support thereon, means for inoperatively positioning a plurality of records thereon, means for automatically and substantially simultaneously throwing one record out of and another record into operative position relative to the carrying member. 70

2. A sound recording and reproducing machine comprising a plurality of continuously moving record carrying members, 75 an independently operative record support thereon, means for inoperatively positioning a plurality of records thereon, means for automatically and substantially simultaneously throwing one record out of and 80 another record into operative position relative to the carrying member.

3. A sound recording and reproducing machine comprising a turntable, a record support, means for inoperatively positioning 85 a record thereon, means for automatically placing said record support and record into operative relation to the turntable at a predetermined time.

4. A sound recording and reproducing machine comprising a turntable, a record support vertically adjustable relative thereto for inoperatively positioning a record, a sound box and its needle, means for automatically positioning said record support 95 and record into operative relation to the turntable at a predetermined time, and a second turntable, record, sound box and its needle for actuating said automatic positioning means. 100

5. In a sound recording and reproducing machine, means for reproducing a plurality of records substantially continuously comprising a plurality of simultaneously operating record carrying members, supports thereon for holding the records in inoperative position, means for locking said supports in operative engagement with the carrying members, and record shifting means including a record shifting lever for throwing one record into and a second record out of operation. 105

6. In a sound recording and reproducing machine, means for reproducing a plurality of records substantially continuously comprising a plurality of simultaneously operating record carrying members, supports thereon for holding the records in inoperative position, a plurality of sound arms, means for locking said supports in operative engagement with the carrying members, record shifting means, including a record shifting lever for throwing one record into and a second record out of operation, and means operatively connecting one 115 of said sound arms with said lever to actuate the same. 120

7. In a sound recording and reproducing machine, means for reproducing a plurality of records substantially continuously, 130

comprising a plurality of simultaneously operating record carrying members, shafts for said carrying members, adjustable supports thereon for holding the records in inoperative position, a plurality of sound arms, interlocking members on said supports and said shafts for locking the supports into operative engagement with said carrying members, record shifting means including a record shifting lever for throwing one record into and a second record out of operation, and means operatively connecting one of the sound arms with said lever to actuate the same.

15 8. In a sound recording and reproducing machine, means for reproducing a plurality of records substantially continuously comprising a plurality of simultaneously operating record carrying members, shafts for 20 said carrying members, pintles thereon for holding the records in inoperative position, a plurality of sound arms, means for locking said pintles into operative engagement with the carrying members, and record 25 shifting means including a record shifting lever, pintle supports and lever positioning members on said lever for throwing one record into and a second record out of operation, and a lever tripping member on one 30 of the sound arms to actuate said lever positioning members.

9. In a sound recording and reproducing machine, means for reproducing a plurality of records substantially continuously comprising a plurality of simultaneously operating record carrying members, shafts for 35 said carrying members, pintles thereon for holding the records in inoperative position, a plurality of sound arms, means for holding 40 said pintles in operative engagement with the carrying members, and record shifting means including a record shifting lever, pintle supports and lever positioning members on said lever, and reversing levers connected with said positioning members for throwing one record into and a second record 45 out of operation, and a lever tripping member on one of said sound arms to actuate said reversing levers.

50 10. In a sound recording and reproducing machine, means for reproducing a plurality of records substantially continuously comprising a plurality of simultaneously operating record carrying members, shafts for 55 said carrying members, pintles thereon for holding the records in inoperative position, a plurality of sound arms, means for holding said pintles in operative engagement with the carrying members, record shifting 60 means including a record shifting lever, pintle supports and lever positioning members on said lever, and a lever tripping member on one of the sound arms to actuate said reversing lever, reversing levers connected 65 with said positioning members, and lever

shifting means for actuating the shifting lever for throwing one record into and a second record out of operation.

11. In a sound recording and reproducing machine, means for reproducing a plurality of records substantially continuously comprising a plurality of simultaneously operating record carrying members, shafts for 70 said carrying members, pintles thereon for holding the records in inoperative position; 75 a plurality of sound arms, means for holding said pintles in operative engagement with the carrying members, and record shifting means including a record shifting lever, pintle supports and lever positioning members on said lever, reversing levers connected with said positioning members, and a lever tripping member on one of said sound arms to actuate said reversing levers, an operating shaft, and lever shifting means actuated 80 thereby for actuating the shifting lever for throwing one record into and another record out of operation.

12. In a sound recording and reproducing machine, means for reproducing a plurality of records substantially continuously comprising a plurality of simultaneously operating record carrying members, shafts for 90 said carrying members, pintles thereon for holding the records in inoperative position, 95 a plurality of sound arms, means for holding said pintles in operative engagement with the carrying members, and record shifting means including a record shifting lever, pintle supports and lever positioning members on said lever, reversing levers connected with said positioning members, and a lever tripping member on one of said sound arms to actuate said reversing levers, an operating shaft, lever shifting means actuated 100 thereby for actuating the shifting lever for throwing one record into and another record out of operation, and controlling means for the shifting means comprising a locking member for the shifting lever also adapted 105 to be engaged by the tripping member before it engages the reversing lever.

13. The combination of a sound reproducing machine having means for reproducing a plurality of records substantially continuously and comprising a plurality of simultaneously operating record carrying members, shafts for said carrying members, pintles thereon for holding the records in inoperative position, means for holding said 115 pintles in operative engagement with the carrying members, a plurality of sound arms, and record shifting means including a record shifting lever, pintle supports and lever positioning members on said lever, reversing levers connected with said positioning members and a lever tripping member on one of said sound arms to actuate said reversing levers, and controlling means for 120 said shifting means comprising a locking 125 member

65 130

member for the shifting lever also adapted to be engaged by the tripping member before it engages the reversing lever with a sound record having a substantially distorted record groove for actuating the record shifting and controlling means.

14. A sound reproducing machine comprising a plurality of automatically, successively rotatable record carrying members, 10 simultaneously rotating record carrying members therefor, a common driving shaft for the record carrying members, and means operated by the shaft for positively placing each of the record carrying members into 15 and out of operation in repeated cycles.

15. A sound reproducing machine comprising a plurality of continuously movable record carrying members, means for continuously moving said members, means for locking a record to each of the record carrying members in succession, and means including a driving shaft for effecting the reproduction of the records in repeated cycles.

16. A sound recording and reproducing 25 machine comprising record carrying members, means for continuously moving said members, means for locking the record tablets to the record carrying members in succession, an operating shaft effecting continuous driving of the machine, and means including a plurality of sound boxes and their needles effecting recording and reproducing of the records in repeated cycles.

17. A sound reproducing machine comprising a plurality of continuously moving record carrying members, means for inoperatively positioning a plurality of records adjacent thereto, means for automatically and substantially simultaneously throwing one 40 record out of and another record into operative position and repeating said operation in cycles.

18. A sound recording and reproducing machine having a plurality of sound record 45 carriers, and means automatically effecting successive operation of the record carriers in repeated cycles.

19. A sound reproducing machine comprising a plurality of turntables, successively 50 operating record carrying members vertically adjustable relative to the turntables, and inoperatively positioned relative to the turntables when in raised position, and means including a plurality of sound boxes, 55 needles, and records effecting automatic, successive, operative positioning of the record carrying members relative to the turntables, in repeated cycles.

20. A sound reproducing machine comprising a plurality of simultaneously operating record carrying members, successively 60 operable record carrying members for holding the records in inoperative position, means for locking the successively operable 65 record carrying members in operative en-

gagement with the simultaneously operating carrying members; and record shifting means including a driving shaft, and a record shifting lever for throwing one record into and a second record out of operation in 70 repeated cycles.

21. A sound reproducing machine comprising simultaneously operating record carrying members, successively operable record carrying members for holding the records in inoperative position, a plurality of sound arms, means for locking the successively operable members in operative engagement with the simultaneously operating record carrying members; and record shifting means including a driving shaft, and a record shifting lever for throwing one record into and a second record out of operation in 75 repeated cycles; and controlling means operatively connecting the sound arms with the shifting lever to control the same.

22. A sound reproducing machine comprising simultaneously operating record carrying members, shafts therefor, adjustable, successively operable, record carrying members for holding the records in inoperative position, a plurality of sound arms, interlocking members on the successively operable carrying members and shafts, for locking the simultaneously operable carrying members into operative engagement therewith; and record shifting means including a driving shaft, and a record shifting lever for simultaneously throwing one record into and a second record out of operation in 80 repeated cycles; and controlling means operatively connecting the sound arms with the shifting lever to control the same.

23. A sound reproducing machine comprising a plurality of simultaneously operating record carrying members, shafts therefor, successively operative record carrying pintles for holding the records in inoperative position, sound arms, means for locking the pintles in operative engagement with the simultaneously operating carrying members; and record shifting means including a driving shaft, and a record shifting lever having pintle supports and lever positioning members thereon for throwing one record into and a second record out of operation in 85 repeated cycles; and controlling means including lever tripping members on the sound arms to control the lever positioning members.

24. A sound reproducing machine comprising a plurality of simultaneously operating record carrying members, shafts therefor, successively operating record carrying pintles for holding the records in inoperative position, sound arms, means for locking the pintles in operative engagement 90 with the simultaneously operating carrying members; and record shifting means including a driving shaft, and a record shifting 95

lever, having pintle supports and lever positioning members thereon; and controlling means including reversing levers operatively connected with the positioning members, and 5 lever tripping members on the sound arms to control the reversing levers for throwing one record into and a second record out of operation in repeated cycles.

25. A sound reproducing machine comprising simultaneously operating record carrying members, shafts therefor, successively operative record carrying pintles for holding the records in inoperative position, a plurality of sound arms, and means for 10 locking the pintles in operative engagement with the simultaneously operating carrying members; record shifting means including a driving shaft, and a record shifting lever having pintle supports and lever positioning 15 members thereon; and controlling means including reversing levers for the positioning members, lever tripping members on the sound arms to actuate the reversing levers; and means for locking the shifting lever to 20 lock one record into and a second record out of operative position in repeated cycles.

26. A sound reproducing machine comprising a plurality of simultaneously operating record carrying members, shafts 30 therefor, successively operative record carrying pintles for holding the records in inoperative position; sound arms, means for holding the pintles in operative engagement with the simultaneously operating carrying members; and record shifting means including a driving shaft, a record shifting lever having pintle supports and lever positioning members thereon, and catches on the positioning members; and controlling means 35 including reversing levers connecting the positioning members, lever tripping members on the sound arms to actuate the reversing levers, and locking levers actuated by the tripping members.

40 27. A sound reproducing machine comprising a plurality of simultaneously operative record carrying members, shafts therefor, successively operative record carrying pintles for holding the records in 45 inoperative position, means for holding the pintles in operative engagement with the successively operable carrying members, and a plurality of sound arms; record shifting means including a driving shaft, a record 50 shifting lever having pintle supports and lever positioning members thereon, and catches on the positioning members; and controlling means including reversing levers

connected with the positioning members, lever tripping members on the sound 60 arms, locking levers for the shifting lever actuated by the tripping members prior to actuation of reversing levers, and lever shifting disks on the driving shaft to actuate the shifting lever. 65

28. A sound reproducing machine comprising a plurality of simultaneously operative record carrying members, hollow shafts therefor, record carrying pintles on the shafts for holding the records in inoperative 70 position, means for locking the records to the pintles, means for holding the pintles in operative engagement with the simultaneously operative record carrying members; a plurality of sound arms, record shifting 75 means including a driving shaft having lever shifting disks, a record shifting lever having pintle supporting means and lever positioning means thereon including catches engaged by the lever shifting disks and 80 springs for the catches; and controlling means including reversing levers, lever tripping members therefor, and locking means for the shifting lever.

29. A sound reproducing machine comprising simultaneously moving record carrying members, balanced successively operating record carrying members operated thereby, means for automatically locking the latter members alternately to the former 90 members, laterally movable sound arms, upwardly moving record shifting mechanism operated thereby to raise the successively operable carrying members from the simultaneously movable members including a 95 shifting lever, positioning members thereon adapted to be thrown into the path of the disks having catches, a shaft having disks thereon, and controlling means including reversing levers operated by the sound arms 100 to control the action of the disks upon the catches.

30. A multiple table sound recording and reproducing machine comprising, continuously operable tables, alternating operable 105 record carrying members independently and positively lockable thereto for immediate equal rotative speed therewith, and means including a shaft and record shifting means for automatically moving the carrying members and records in opposite directions. 110

In testimony whereof I have signed my name to this specification.

ALFONSO CORTELLA.
